N. Weiler.

UNITED STATES PATENT OFFICE.

NICK WEILER, OF SIOUX CITY, IOWA, ASSIGNOR, BY DIRECT AND MESNE ASSIGNMENTS, OF ONE-FOURTH TO CHARLES W. SWANSON AND ONE-FOURTH TO LYMAN J. RANDOLPH, OF SIOUX CITY, IOWA.

SWINGING STACKER.

No. 799,212.

Specification of Letters Patent.

Patented Sept. 12, 1905.

Application filed April 18, 1905. Serial No. 256,834.

To all whom it may concern:

Be it known that I, NICK WEILER, a citizen of the United States, residing at Sioux City, in the county of Woodbury and State of Iowa, have invented a new and useful Improvement in Swinging Stackers; and I do declare the following to be a full, clear, and exact description of the same, reference being had to the accompanying drawings, forming a part thereof.

10 My invention relates to swinging stackers for threshing-machines, and particularly to that kind which automatically swing from side to side during its operation. The object of my invention is to provide means for operating the stacker in this manner.

The invention consists of the mechanism for simply and automatically regulating the operation of the stacker, as will be more fully described in the claim.

20 In the drawings, Figure 1 is a plan view of mechanism for swinging the stacker. Fig. 2 is a side view of rear end of thresher with the stacker shown in Fig. 1 attached. Fig. 3 is an enlarged detail view of mechanism for 25 operating the stacker shown in Fig. 1. Fig. 4 is a detail view of shaft and pinion shown in Figs. 3 and 4. Fig. 5 is a side view of wheels and pinions shown in Figs. 1 and 3. Fig. 6 is a detail plan view of device for operating 30 shifting bar. Fig. 7 is a side view of same. Fig. 8 is an enlarged view of head of shifting bar. Fig. 9 is a side view of the same with the device inclosed.

Like parts are designated by similar letters 35 of reference,

T is the rear end of the thresher, the carrier being operated by the chain-wheels t' and t'' , chain t^3 , pulleys t^4 and t^5 , and belt t^6 . The swinging stacker is pivotally secured to the frame B by means of a bolt t^8 .

U is the segment of a circle, pivotally secured to the frame at the center by means of the bolt t^8 . The segment is ratched or cogged on its circumference and is firmly attached to the frame t by means of a connecting-plate-form u . On the inner rim of the segment are provided holes v v . The segment is operated by means of a shaft u' , to which is secured a worm-wheel u^2 , which engages the teeth of the segment. At the outer end of the shaft is a sprocket-wheel u^3 , adapted to turn on the shaft and connected with the operating part of the thresher by a chain u^4 . To the inner side

of the sprocket-wheel is secured a wheel u^5 , having inside teeth or cogs and adapted to 55 turn with the sprocket-wheel freely on the shaft. It meshes with a pinion u^6 , secured to the shaft v' , parallel with the shaft u' . To the inner end of the shaft v' is secured a 60 cogged wheel v^2 , adapted to mesh with a cogged wheel v^3 , secured to the shaft u' . The wheels u^5 and v^3 have hubs u^7 and v^4 , respectively, the hubs facing each other and being cut out around the shaft. Between the hubs is a smooth wheel w , keyed upon the shaft, 65 as seen in Fig. 3, and adapted to slide upon it. The wheel is provided with laterally-projecting lugs w' and w'' , which are adapted to engage the cut-out parts of the hubs. The wheel w is encircled by a loose ring w^2 , keyed 70 upon it, as seen in Fig. 4, the wheel being adapted to revolve within the ring. A rod w^3 is pivoted to the ring and pivotally secured to the frame at the point w^4 . It is then pivotally connected at right angles to a shifting 75 bar w^5 , having a head w^6 and lugs w^7 and w^8 . Within the head of the bar is a heart-shaped device w^9 , pivotally secured to the frame. Pins x and x' , secured to the heart-shaped device, project upward therefrom, and a rod x'' , 80 pivoted at one end to the frame, extends between the pins and over the segment. A spring w^9 is secured at one end to the frame and at the other end to the rod x'' near its secured end. Pins y and y' are adapted for 85 adjustment in the holes v v in the segment. In Fig. 1 of the drawings the segment is shown moving from right to left. The left lug of the wheel w is shown in engagement with the hub of the wheel v^3 , which operates the shaft u' by means of the cogged wheel v^2 , shaft v' , pinion u^6 , cogged wheels u^5 , and chain-wheel u^3 , to which the power is applied from the thresher by means of the chain u^4 . When the pin y strikes the rod x'' , it will cause the heart-shaped device to turn to the left, striking the cam w^9 and pushing the shifting bar to the left, releasing the lug w'' from the hub v^4 and forcing it into the hub u^7 . The wheel w being keyed upon the shaft u' , the chain-wheel u^3 now operates the shaft directly, as shown in Fig. 3, reversing the movement of the segment. The movement of reversing the segment will continue while the stacker is in operation.

Having described my invention, what I

claim as new, and desire to secure by Letters Patent, is—

In a swinging stacker, the combination of a carrier, a frame to which the carrier is pivotally secured, a segment having teeth on its circumference and holes for the insertion of pins, a worm-wheel adapted to engage the teeth of said segment and a shaft to which the worm-wheel is secured, a cogged wheel secured to said shaft having a hub with a cut-out portion around the shaft, a wheel at the outer end of said shaft adapted to turn freely thereon, means for imparting motion to said wheel, a wheel with inside teeth secured to said outer wheel, adapted to turn freely on said shaft and having a hub with a cut-out portion around the shaft, said hubs facing each other, a shaft parallel with said first shaft adapted to revolve in bearings in the frame, a cogged wheel secured to one end of said shaft and adapted to mesh with the wheel secured to said first shaft, a pinion secured to the opposite end of said second shaft and adapted to mesh with the wheel with inside teeth, a

wheel keyed to said first shaft between said hubs and adapted to slide upon the shaft, a ring encircling said wheel, and keyed thereto, a lever pivotally secured at one end to said ring and pivotally secured near the middle to the frame, a bar pivotally secured to the opposite end of said lever, a heart-shaped device at the end of said bar pivotally secured to the frame and having pins extending upward therefrom, cams at the end of said bar inclosing said device, a rod pivotally secured to the frame, extending over the segment between the pins in said device and adapted to come in contact with the pins in said segment, and a spring for holding said rod in position, substantially as described.

In testimony whereof I have hereunto affixed my signature in the presence of two witnesses.

NICK WEILER.
